UNITED STATES PATENT OFFICE.

CHARLES A. PRINDLE, OF CHICAGO, ILLINOIS.

CHAIN.

1,196,396.

Specification of Letters Patent. Patented Aug. 29, 1916.

Application filed October 14, 1911. Serial No. 654,609.

To all whom it may concern:

Be it known that I, CHARLES A. PRINDLE, a citizen of the United States, residing at Chicago, in the county of Cook and State 5 of Illinois, have invented certain new and useful Improvements in Chains, of which the following is a description.

My invention belongs to that general class of devices known as chains, and relates particularly to chains for transmitting power.

The invention has among its objects the production of a chain that is simple, convenient, durable, efficient and satisfactory, that may be used wherever found applicable.

The invention herein described is similar to that described in my Patent No. 1,058,260, granted April 8, 1913.

To this end my invention consists in the novel construction, arrangement and combination of parts herein shown and described, and more particularly pointed out in the claims.

In the drawings, wherein like reference characters indicate like or corresponding parts, Figure 1 is a plan view and partial sectional view of several assembled links, illustrating one form of my chain. Fig. 2 is a side elevation and a partial sectional view of the same. Fig. 3 is a cross sectional view taken substantially on line 3, 3 of Fig. 1. Fig. 4 is a perspective view of a portion of one of the links. Fig. 5 is a perspective view of the coöperating part of the link. Fig. 6 is a plan view and partial sectional view of several assembled links, illustrating another form of my device. Fig. 7 is a side elevation and partial sectional view of the same. Fig. 8 is a sectional view taken substantially on line 8, 8 of Fig. 7. Fig. 9 is a partial sectional and plan view of the parts of two links of another form of my device. Fig. 10 is a sectional view of the same taken substantially on line 10, 10 of Fig. 9, and Fig. 11 is a partial sectional and plan view of the parts of several assembled links showing a slightly modified construction.

In the drawings are illustrated several forms of my improved chain, the form 50 shown in Figs. 6, 7 and 8 being that shown and described in my pending application mentioned. The remaining figures illustrate several slightly different forms.

Referring to the form of chain shown in 55 Figs. 1 to 5 inclusive, the chain comprises a plurality of links, each link of which is

made up of a plurality of parts forming a shank, with means at the ends for engagement with the adjacent links. One part of the link comprises a shank 1 provided at one 60 end with a truncated conical lateral projection 5, the opposite end of the shank being provided with a cup-shaped end 2 having a recess 3 therein of a shape corresponding to the lateral projection 5. The co-operating link part consists of a shank 11 provided with a similarly formed cup-shaped end 12, having a recess 13 therein, and provided with a lateral projection 15 at the opposite end. The cup-shaped ends 70 2 and 12 are cut away as at 4 and 14 respectively, and preferably rounded at the points 8 and 18 respectively. One of the shanks, as shown the shank 1, is provided with an extending part or lug 7, and the other part 75 with an opening 16 therethrough, the outer side of the shank 11 being preferably countersunk on the outer side, as at 17. The parts of each link are secured together by assembling them with the part 7 on one 80 shank extending through the opening 16 in the other shank, and then upsetting the end of the part 7, as indicated at the right hand of Fig. 1. With this construction the links are secured together without any additional 85 securing means, so that each link comprises only two parts. The lug also constitutes means for accurately mating or alining the link parts in assembling. The cup-shaped ends 2 and 12, it will be noted, are preferably 90 not cut through at the bottom of the recesses 3 and 13, but left as at 9 and 19 respectively, so that the link is not weakened in any way. In the form shown in Figs. 6, 7 and 8, which, as previously mentioned, is 95 the same form described in my pending application, each of the links is made up of two parts, comprising two shanks 25 and 26, arranged to be secured together. The shank 25 is provided with a semi-spherical 100 or cup-shaped end 29 at one end with an extending part 27 at the opposite end, while the opposite part or half of the link is provided with similar parts 30 and 28 respectively on the shank 26. The semi-spherical or cup-shaped parts 29 and 30 are recessed to receive the parts 27 and 28 of the adjacent link, the cup-shaped ends being open as at 32 and 33 respectively, so as to permit movement of the connecting or adjacent 105 link. The links are assembled by inserting the ends 27 and 28 of the two halves of the

link in the cup-shaped or recessed ends 29 and 30 of the adjacent link, and then riveting or otherwise securing the two parts of each link together by means of rivets or pins 31 and 34, or their equivalents.

In Figs. 9 and 10, substantially similar links are shown, each comprising the shanks 20 and 21 having similarly cup-shaped ends 22 and extending parts 23. In this form 10 the cup-shaped ends are left with a portion of the material at 9¹ and 19¹, as in the form shown in Fig. 1. The two parts of each link and the parts of the adjacent link are secured together by rivets or pins 24 and 36.

15 The links shown in Fig. 11 are substantially the same as those previously described, except that they are arranged to swivel. Referring to Fig. 11, each link comprises shanks 40 and 41, which may be secured 20 together by a pin 42, as shown, or in an equivalent manner. The shank parts are provided with cup-shaped ends 43 and 44 respectively, and with semi-spherical extending ends 45 and 46. Openings or slots 25 47 are provided in the cup-shaped ends 43 and 44, similar to those previously described for the other forms. In this case the shanks may be rounded as at 48 to facilitate the swivel, and so as not to require as wide a 30 space between the links as if the shank of the link were square.

It is of course obvious that the links may be of any desired size or manufactured of any suitable material. While the link is particularly applicable for use on agricultural machinery, vehicles, conveyers, hoisting machinery, and the like, it may be used wherever found applicable.

Having thus described my invention, it 40 is obvious that various immaterial modifications may be made in the same without departing from the spirit of my invention, hence I do not wish to be understood as limiting myself to the exact form, construction or combination of parts herein shown and described, or uses mentioned.

What I claim as new and desire to secure by Letters Patent is:—

50 1. A chain including a plurality of similarly formed links, each link comprising two similarly formed parts adapted to be placed together, each part consisting of a shank

portion provided with a recess at one end thereof and at its other end with a portion extending laterally on the side opposite the recess, the links being assembled with the laterally extending portions of one link positioned in the recesses of the adjacent link, one link part being provided with a substantially oblong shaped opening through 55 the shank thereof intermediate its ends, and the other link part having a lug projecting laterally from its shank intermediate the ends thereof, said lug being formed as an integral part of the shank and of a size and 60 shape in cross section to fit the said opening in the shank of the other link, the lug being adapted to be fitted into the opening in assembling the link parts and said lug being of a length to extend through the opening 65 70 adapted to be upset to secure the link parts together.

2. A chain including a plurality of similarly formed links, each link comprising two similarly formed parts adapted to be placed together, each part consisting of a shank portion provided with a recess at one end thereof and at its other end with a portion extending laterally on the side opposite the recess, the links being assembled 75 with the laterally extending portions of one link positioned in the recesses of the adjacent link, and separate means for securing the parts of each link together, said means comprising a lug projecting laterally from 80 the shank portion of one link part intermediate the ends thereof and formed integral therewith, the other link part being provided with an opening extending through 85 the shank portion thereof intermediate its 90 ends, said lug being of a size and shape in cross section to fit the said opening, the lug being adapted to be fitted into the opening in assembling the link parts, and said lug being of a length to extend through the 95 opening and adapted to be upset to secure the link parts together.

In testimony whereof, I have hereunto signed my name in the presence of two subscribing witnesses.

CHARLES A. PRINDLE.
